ELECTRICALLY OPERATING WEFT DETECTING SHUTTLE

Application filed September 26, 1930. Serial No. 484,596.

This invention relates to improvements in spindle shuttles constructed to detect the condition of weft, and it is the general object of the invention to improve shuttles of this type and provide a detecting element which is conveniently and substantially mounted.

The usual spindle shuttle has a transverse pivot pin about which the bobbin holding spindle moves to permit removal of an exhausted weft carrier. It is an important object of my present invention to provide a weft detecting element, preferably to cooperate with an electrical circuit, mounted on the pivot pin of the spindle so as to render unnecessary the provision of an additional pivot for the detecting element.

Shuttles of the type specified usually have some form of spring clip which holds the spindle in both its normal down position and also the inclined position it assumes to permit manipulation of the weft carrier. It is an important object of my present invention to construct the detecting lever so that it will be held by this spring within the outline of the split spindle where it cannot interfere with longitudinal movement of a weft carrier when the spindle is raised to remove the carrier.

It is a still further object of my invention to provide a light yielding spring or similar device located between the usual flat spring and a portion of the detecting lever tending to move the latter normally to indicating position but prevented from accomplishing this result by weft presence.

The detecting lever moves preferably vertically in an upright slot cut in the head end of the spindle. It is another object of my invention to provide a resilient means to hold the spindle parts separated so that they will not clamp against the detector lever and interfere with free movement of the latter, said resilient member also being so placed as to serve as a stop to limit movement of the detector lever in one direction.

With these and other objects in view which will appear as the description proceeds, my invention resides in the combination and arrangement of parts hereinafter described and set forth in the claims.

In the accompanying drawing wherein a

convenient embodiment of my invention is set forth,

Fig. 1 is a vertical section through the central axis of a shuttle made according to my present invention, the tip ends of the shuttle being shown in elevation, the detector lever being in non-indicating position,

Fig. 2 is a top plan view taken in the direction of arrow 2, Fig. 1, showing the cap and mass of weft thereon in section, part of the top spring which co-acts with the spindle being removed for the sake of clearness,

Fig. 3 is a view similar to a portion of Fig. 1 but with the detecting lever moved to indicating position,

Fig. 4 is a vertical transverse section on line 4—4 of Fig. 3,

Fig. 5 is a view similar to Fig. 3 but with the spindle in elevated position and showing the detector lever moved out of the path of the weft carrier by the top spring, and

Fig. 6 is an enlarged top plan view similar to a portion of Fig. 2 showing the relation of the spring which separates the two legs of the spindle and acts also as a stop for the detector lever.

Referring to the drawing, the shuttle S is provided with a transverse pivot pin 10 on which is mounted a spindle 11. The latter has two resilient legs 12 and 13, respectively, which, as shown in Fig. 2, are joined together as by welding to form a tip 14. Each of said legs is provided with a head 15 having a downwardly opening slot 16 fitted over the pivot pin 10. An upper or top leaf spring 17 is held to the shuttle by a screw 18 and co-acts with the heads to hold the spindle normally down in the position shown in Fig. 1 with a lip 19 on one or both heads engaging a portion of the shuttle body to limit angular movement of the spindle in a right hand direction as viewed in Fig. 1.

The two legs are spaced and define between them a vertical slot 20 in which is mounted an electrical weft detector lever 21 the right hand end of which as shown in Fig. 1 is provided with a rounded projection or yarn engaging finger 22. The lever has a downwardly opening slot 23 formed in the head or left end thereof as viewed in Fig. 1 to fit over

the pin 10 between the heads 15. A small arm 24 extends from the lever and receives the downward thrust of a light compression spring 25 located in a pocket 26 lying between the top leaf spring 17 and the arm 24. The spring 25 serves normally to lift the finger 22 and tends to move the detector lever to indicating position.

Mounted on the spindle is a weft carrier 10 or cop 27 having a slot 28 positioned to register with the finger 22. The latter normally engages the coils of smallest diameter on the carrier lying across the slot and are held by them against upward movement under action 15 of spring 25.

As shown in Fig. 6 the legs 12 and 13 are provided with aligning pockets 29 which receive opposite ends of a small stiff compression spring 30 which tends normally to hold the legs in spaced relation so they will not cramp the lever. This spring also engages the bottom of the lever to limit downward movement of the latter with respect to the spindle.

25. The shuttle is particularly adaptable for electrical indication of weft exhaustion and has in one wall thereof contact plates 31 and 32 which are placed to contact with brushes 33 and 34, respectively, every alternate beat 30 of the loom. Plate 32 has electrical connection with the pin 10 and is therefore electrically connected at all times with the lever, the spring 25 assisting in maintaining good electrical contact between the pin and the lever. 35. The other plate 31 is connected by means of a wire 35 to a bottom leaf spring 36 held by means of a screw 37 to the body of the shuttle and having a free inwardly projecting end 38 provided with a rib 39. The latter is normally positioned out of contact with an arm 40 depending from the lever. The upper end of the lever is provided with a notch 41 positioned for engagement with the inner end of the upper spring 17 when the spindle is 45 raised.

Under normal conditions when a sufficient supply of weft is present the finger 22 will be confined within the outline of the carrier 27, or will be held in the relatively low position shown in Fig. 1 with arm 40 out of contact with the rib 39. Under these conditions there is no electrical connection between the plates 31 and 32 and the loom continues to operate without change. When the weft becomes sufficiently depleted to uncover the slot 28; however, the finger 22 will move upwardly therethrough around the pivot 10 under influence of the light compression spring 25. This angular movement of the lever will bring the arm 40 into contact with the rib 39, thereby electrically connecting the plates 31 and 32 so that the brushes in contact with the plates may close an external circuit not shown and thereby effect a change in the 60 operation of the loom. This change may

cause either stopping of the loom or an exchange of shuttles, and it will subsequently be necessary for the operator to remove the spent weft carrier and replace it with one having a full supply of yarn.

70 In order to remove the old cop the spindle is moved to the inclined elevated position shown in Fig. 5. It will be noted that as the spindle is raised the top spring 17 will engage a surface 41 of the lever and positively lower the latter to move the finger 22 to a position within the outline of the spindle, thereby permitting the cop or weft carrier to be removed.

75 The spindle has the usual screw thread T 80 which cuts into the inner surface of the cop to hold the latter in place. A rotary movement of the cop is necessary to place it on, or remove it from the spindle, and it is for this reason that finger 22 must be moved out of the slot in the cop so as to permit free turning of the latter. This result is accomplished by the mechanism just described.

85 The springs 17 and 30 are so placed that the downward force exerted by the former will pass between the pivot pin 10 and the compression spring 30 which acts as a stop for the lever. In this way the lever is held in a definite position with its detecting end located within the outline of the spindle and the finger out of the slot 28 in the cop. If desired the under side of the lever can be so constructed as to engage a solid part of the cop at all times when the spindle is inclined and thereby prevent the under side of the 95 lever from entering the slot.

90 When the spindle is elevated to the position shown in Fig. 5 the top leaf spring 17 will coact with the heads 15 to hold the spindle raised. During the lifting of the spindle 105 lower spring 36 yields as arm 40 passes from the outer to the inner side of the rib 39, moving from the position shown in Fig. 3 to that shown in Fig. 5.

110 When the fresh cop is being applied to the spindle the detector lever will remain in the position shown in Fig. 5 so as not to interfere with rotary movement of the cop. The proper longitudinal and angular position of the cop is determined by means of a marker 115 or the like so as to cause the slot 28 to register with the finger 22, after which the spindle may be depressed to the position shown in Fig. 1. This latter movement will reestablish connection between the spring 25 and the arm 24 and presence of yarn across the slot 28 will hold the arm 40 out of contact with the rib 39.

120 From the foregoing it will be seen that I have provided a spindle shuttle wherein the weft engaging detecting lever is mounted on the spindle pivot and movable in the slot between the two legs of the spindle. Furthermore, the spring at the top of the shuttle which co-acts in the usual way with the spin- 130

dle head serves also to depress the detector lever so that the finger end of the latter will move out of slot 28 in the cop, thereby permitting uninterrupted rotary movement of the cop around the spindle. It will also be seen that the light spring 25 pushes downwardly on the arm 24 to insure good contact between the lever and its pivotal support 10 and also requires the finger 22 to move against the yarn on the carrier. It will be further noted that the small stiff coiled spring which holds the spindle legs separated acts as a stop for the detector lever and is so placed that the top flat spring 17 may co-act with the pivot pin 10 and the stiff spring 30 to place the lever accurately and definitely within the cutline of the spindle.

Having thus described my invention it will be seen that changes and modifications may be made therein by those skilled in the art without departing from the spirit and scope of the invention and I do not wish to be limited to the details herein disclosed, but what I claim is:

1. In a shuttle, a spindle to hold a supply of weft and having a slot, a pivot for the spindle extending across the slot and around which the spindle moves, a detector element in the slot pivotally mounted on the spindle pivot and normally held in a given position when a sufficient supply of weft is present, and limited as to movements in opposite directions along the pivot by the spindle, and means acting at weft exhaustion to move the element angularly from the given to an indicating position about the spindle pivot when the supply of weft is exhausted.

2. In a shuttle, a spindle having a longitudinally extending slot therein, a pivot for the spindle carried by the shuttle and extending across the slot, a detector lever located in the slot and movable about and supported by the spindle pivot, and limited as to movements in opposite directions along the pivot by the spindle, the lever normally held in a given position when sufficient weft is present, and means effective to move the lever angularly from said normal to an indicating position about the pivot when insufficient weft is present.

3. In a shuttle, a spindle to carry a supply of weft, a pivot for the spindle, said spindle having a vertical longitudinally extending slot therein, a pair of spaced heads on the spindle, one on each side of the slot, mounted on the pivot, a detector lever having pivotal connection with the spindle pivot between the heads, and means effective at weft exhaustion to move the detector lever about the spindle pivot to exhaustion indicating position.

4. In a shuttle, a spindle to carry a supply of weft, a pivot for the spindle, said spindle having a pair of spaced longitudinally extending legs each mounted on the pivot, a

weft detector lever mounted on the spindle pivot between the legs, and normally acting yielding means to move the detector lever about the spindle pivot to indicating position when insufficient weft remains on the spindle. 70

5. In a shuttle, a weft supporting spindle having a slot, a weft detecting element, located in the slot and limited as to lateral movements in opposite directions by the spindle, and a common pivotal support for the spindle and element about which the latter moves pivotally when indicating weft exhaustion. 75

6. In a shuttle, a weft carrying spindle pivoted thereto, a weft detecting finger movable from a position within the spindle to a position partly out of the spindle to indicate weft exhaustion, and common means to hold the spindle in inclined weft receiving position and also to hold the detector finger within the spindle. 80 85

7. In a shuttle, a weft carrying spindle pivoted thereto, a weft detecting finger normally located within the outline of the spindle and movable to a position projecting beyond the spindle outline to indicate weft exhaustion, and means to hold the spindle in inclined position to receive a fresh supply of weft, said means effective when the spindle is so inclined to move the finger to a position within the outline of the spindle, where it will be out of interfering engagement with the fresh supply of weft. 90 95

8. In a shuttle, a weft carrying spindle pivoted thereto, the spindle adapted to hold a weft carrier having a slot therein which may be rotated about the spindle when being applied thereto, a detector finger to lie normally within the carrier when sufficient weft is present, and tending to move through the slot to indicate weft exhaustion, and means to hold the spindle in inclined position to receive a fresh supply of weft, said means also preventing the finger from entering the slot as the carrier is rotated on the spindle while the latter is in inclined position. 100 105 110

9. In a shuttle, a weft carrying spindle pivoted thereto, a weft carrier slidably and rotatably mounted on the spindle and having a detecting slot therein across which weft extends when sufficient weft is present, a detector finger movable from a position within the carrier through the slot to indicate weft exhaustion, said finger tending normally to move through the slot, and means to hold the spindle in inclined position to receive a fresh supply of weft, said means effective when the spindle is so inclined to prevent the finger from entering the slot as the carrier is rotated on the spindle. 115 120 125

10. In a shuttle, a weft carrying spindle having a mass of weft thereon, a pivot therefore, a rigid detector lever mounted on the spindle pivot, a detector finger forming part 130

of the lever and located normally within the wound mass of weft and tending to move outwardly, and yielding means acting on the lever to move the finger against the weft and effective at weft exhaustion to move the finger outwardly and angularly about the spindle pivot, the pivot and lever forming part of an electric indicating circuit, and the yielding means insuring good contact between the lever and pivot as well as effective to give indicating movement to the finger.

11. In a shuttle, a spindle pivoted thereto and movable to an inclined position to receive a fresh supply of weft, said spindle being formed of two spaced resilient legs, a detector finger located between the legs, a relatively strong resilient element located between the legs to hold them apart to insure clearance for the finger so the latter may move freely, said resilient element acting as a stop to limit movement of the finger relatively to the spindle in one direction.

12. In a shuttle, a pivoted spindle having two spaced legs, a relatively strong resilient element tending to separate the legs, a detector finger located between the legs and movable transversely of the spindle in one direction to indicate weft exhaustion, and means to hold the spindle in inclined position relatively to the weft to receive a fresh supply of weft, said means engaging the finger when the spindle is inclined to move the same in a direction opposite to that in which it moves to indicate exhaustion, said resilient element acting as a stop to limit the last named movement of the finger caused by the means.

13. In a shuttle, a spindle pivoted to the shuttle to be moved upwardly from a position within the shuttle to a position inclined to the longitudinal axis of the shuttle, a detector lever pivoted with respect to the shuttle and moving with the spindle as the latter is raised, a resilient electric contact for the detector element, a sufficient supply of weft on the spindle holding the detector element out of engagement with the resilient contact, means to move the detector element into electrical engagement with the resilient contact at exhaustion of weft when the spindle is housed within the shuttle, the resilient contact yielding when the spindle is raised to permit the contact element to move with the spindle beyond normal contacting position.

14. In a shuttle, a spindle having a vertical slot therethrough to form two resilient legs, a weft detector movably mounted in the slot, a horizontal pivot for the spindle about which the latter swings when raised, the detector movable in the same plane as that in which the spindle swings, and means effective when the spindle is raised to move

the detector in the slot in a direction parallel to the spindle movement.

In testimony whereof I have hereunto affixed my signature.
